UNITED STATES PATENT OFFICE.

JOHN C. DOANE, OF HARTFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed November 25, 1921. Serial No. 517,453.

To all whom it may concern:

Be it known that I, JOHN C. DOANE, a citizen of the United States, residing in Hartford, in the county of Hartford and 5 State of Connecticut, have invented certain new and useful Improvements in Type-writing Machines, of which the following is a specification.

This invention relates to center guides for 10 the type-bars in writing machines, and is illustrated in connection with an Underwood machine, in which thin sheet-metal type-bars are provided with tongues to enter the slot in the guide as they approach 15 the platen.

In said Underwood machine, the guide is fixed to a segment which carries the type-bars, and extends upwardly from the segment and carries at its upper end a pair of 20 flaring guide-nibs or jaws.

It is important to form these jaws of such contour as to eliminate corners against which the type-bars could strike. The guide is made of high grade steel and is of heavy 25 construction, and its guiding surfaces must be machined into form. The machining presents serious practical difficulties, owing to the narrowness of the space between the guiding surfaces, such spaces being only 30 wide enough to admit a thin tongue of the type-bar, and hence affording too little room for the play of the necessary tools.

One of the features of the present invention resides in making said guide-surfaces 35 of an improved contour, whereby the rear part of the guide is given parallel walls or guide-surfaces, which merge forwardly into diverging or flaring gently curved guide-surfaces, thus avoiding any corners between 40 the straight and flaring portions of the guide. These gradually curving surfaces terminate at their outer ends in more flaring portions, thus completing the contour.

The present invention includes further im- 45 provements relating to constructing the guide in such a manner as to render feasible the desired machining of the guide-surfaces during manufacture. To this end, the guide is formed of two entirely separate 50 right and left hand sections, each section carrying one of the guide-nibs or jaws. This permits each jaw to be given exactly the desired contour and finish.

These sections are placed side by side

upon the segment, thereby bringing the jaws 55 into co-operative type-guiding relation, and preferably each section is rigidly secured in position upon the segment independently of the other section.

In order to provide for delicate adjustment of each jaw towards or away from the other, the base-portion of each section is provided with an adjusting device whereby the jaw belonging thereto can be set a trifle 60 to the left or to the right as required. This 65 adjustment is effected by means of two cone-headed screws fitting in holes in each of the two section-bases. Each base is slotted, the slots being open and extending through the screw-holes and approaching each other 70 close enough to permit slight bending or springing of the overhead portion of the section. The lower portion of each section-base is pinned to the segment, and the upper 75 portion of the base is perforated for a fastening screw which is threaded into the segment. Hence, in each section-base, one cone-screw may be loosened and the other may be turned in, thereby opening its slot a trifle 80 and closing the other slot correspondingly, while the jaw at the upper end of the guide-section is swung a trifle to the left or right, as the case may be.

Other features and advantages will hereinafter appear.

In the accompanying drawings,

Figure 1 is a front elevation of the invention in one form, as applied to the type-bar segment of an Underwood machine.

Figure 2 is a plan of the improved guide.

Figure 3 is a sectional side elevation of parts seen in Figure 1.

Figure 4 is a perspective view of one of the sections, and of one of the cone-headed screws and the keyed nut with which it operates.

Figure 5 is an enlarged fragmentary view, showing diagrammatically the cone-headed screws and nuts, and the manner in which they co-operate with a guide-section.

The type-bars 10 are operated by levers 11, and swing about a fulcrum-wire 12 to strike against a platen 13. The fulcrum-wire is mounted in a segment 14, radially slotted at 15 for the type-bars, and carrying 105 a type-bar guide which comprises opposing jaws or members 16. These jaws, at their rear ends, are so formed as to constitute

a straight or parallel-sided directrix for the type-bars at 17, when the same is in or close to printing position. These straight parallel sides merge into forward slightly convex portions 18, thereby eliminating corners. The portions 18 flare outwardly, and terminate in still more flaring portions 19 at the tips of the jaws. Owing to the absence of corners, the type-bar is guided smoothly and accurately to the platen, lateral vibration of the type is reduced, and wear is avoided.

In order to produce the guiding walls cheaply and successfully, notwithstanding the close proximity of the jaws, the type-guide is made in two sections, being for this purpose split from top to bottom at its middle line 20. This permits each section to be manufactured separately, so that the exact contour desired may be produced upon each jaw rapidly and economically. The right section is marked 21 and the left section 22, and from each section arises a post 23, surmounted by a guide-jaw 16. 25 Each section is integral with its post and jaw.

Each section is accurately positioned on the front vertical face of the segment by a pair of pins 24 extending through the lowermost portion of the section. Above the pins the section is transversely slotted at 25, the slots being open and extending from the side edges nearly to a meeting point. The portion 26 of the section remaining between the inner ends of the slots 25 is so narrow as to permit a slight springing of the upper portion of the section to be effected, for the purpose of adjusting the jaw 16 thereon to the right or left.

40 This adjustment may be effected by means of cone-headed screws 27 inserted through tapering holes 28 in the section 21, these holes being coincident with the slots 25. Each screw is threaded into a nut 29, and these nuts may occupy oversize perforations 30 in the segment 14, Figures 3 and 5. Each nut may be provided with a key 31, Figures 4 and 5, and these keys may enter the slots 25, thus preventing the nut from turning.

55 After the type-guide sections are in place on the segment, either the left-hand or the right-hand spreading screw 27 of either section may be loosened, and the other one tightened to open its associated slot 25, and thereby swing the post 23 and its jaw 16 to the right or left as desired. Thereupon the section may be firmly secured to the segment and the adjustment preserved by means of a screw 32, of which each section has one, said screw passing through an oversize perforation 33 in the section and clamping the same to the segment. Each screw 32 is located between the jaw and the adjusting screws 27, so as to clamp the upper

portion of the section in the exact position to which it is adjusted by the use of the cone-headed screws.

Variations may be resorted to within the scope of the invention, and portions of the 70 improvements may be used without others.

Having thus described my invention, I claim:

1. In a typewriting machine, a type-segment, and a type-guide comprising a 75 pair of guide-jaws parallel at their rear portions and merging into curved flaring guide-surfaces, and a pair of separate jaw-carrying sections, each arranged to be placed in the machine separately from and independently of the other, and each comprising means for fitting it to the type-segment against rotary or bodily movement, means for bending it when so fitted toward right or left to adjust the jaw carried by it independently of the other jaw and relatively to the machine, and means for securing the bent section to the segment in adjusted position.

2. In a typewriting machine, a type-segment, and a type-guide consisting of a pair 90 of guide-jaws, and separable jaw-carrying sections, each comprising members at its lower end for fitting it to the type-segment against rotary or bodily movement, means 95 for bending the section above the fitting members to finely adjust the position of the jaw carried by the section, and means above the bending means for securing the section firmly to the segment, and fixing the position of the jaw.

3. In a typewriting machine, a type-segment, and a type-guide comprising a pair of sections, and guide-jaws carried by the sections at their upper ends, each section including means at its lower end for locating it in mechanically-predetermined position relatively to the type-segment, means for bending a portion of the section to adjust the position of the jaw carried by it, and means for securing the section to the segment above the bending means after the desired adjustment has been attained, to assist in fixing the position of the guide-jaw.

4. In a typewriting machine, a set of types, a type-segment, and a type-guide comprising a pair of sections, and complementary guide-jaws carried by the sections at their upper ends, each section comprising means for fitting it upon the segment, means for bending it toward right or left independently of the other section to finely adjust and thereby to correctly locate the jaw carried by it with reference to the paths of the types, said bending means being effective to retain the section in adjusted position, so that the accuracy of the adjustment may be tested and further adjustment may be made without securing the section to the segment in each adjusted position, and

means for firmly securing the section against further adjustment and against vibration when the jaw has been correctly located, to fix its jaw in final adjusted position.

- 5 5. In a typewriting machine, a type-segment, and a type-guide comprising a pair of guide-jaws parallel at their rear when in place on the machine, and a pair of jaw-carrying sections separately insertable in
- 10 the machine, and each comprising means for fitting it to the type-segment, and means for bending it toward right or left independently of the other section to adjust the position of the jaw carried by it, and adjustable
- 15 to resist further bending of the section in the same direction when the desired adjusted position of the jaw has been attained, to prevent vibration of the section when in use.
- 20 6. A type-guide comprising a pair of guiding jaws and divided into two sections, each section carrying one of said jaws, each section having transverse slots on its opposite sides to permit springing or swaying 25 of the section, and means for adjusting said section.
- 25 7. A type-guide comprising a pair of guiding jaws and divided into two sections, each section carrying one of said jaws, each section having transverse slots on its opposite sides to permit springing or swaying of the section, and cone-headed screws working in said slots for springing or adjusting the section.
- 30 8. A type-guide comprising a pair of guiding jaws and divided into two sections, each section carrying one of said jaws, each sec-

tion having transverse slots on its opposite sides to permit springing or swaying of the section, cone-headed screws working in said 40 slots for springing or adjusting the section, said section provided with perforations to receive said cone screws, and nuts carried by the segment, said screws being threaded into said nuts, and means being 45 provided for keying the nuts against rotation.

9. In a typewriting machine, a set of types, a type-segment, and a type-guide for guiding the types to the printing point, comprising a pair of complementary guide-jaws and a pair of jaw-carrying sections, each section including means for fitting it to the type-segment against rotary or bodily movement, means movable substantial distances for bending it through relatively minute distances, when so fitted, toward right or left independently of the other section to finely adjust the jaw carried by it independently of the other jaw and relatively to the machine, and means for securing each bent section to the segment independently of the other, to fix it permanently against further movement when it has been located in its correct adjusted position, the construction and arrangement being such that either section may be adjusted and may then be held stationary throughout the adjustment of the other section.
